UNITED STATES PATENT OFFICE.

ISADOR LEHMAN, OF CLEVELAND, OHIO.

ENGINE.

No. 814,145.

Specification of Letters Patent.

Patented March 6, 1906.

Application filed October 10, 1904. Serial No. 227,848.

To all whom it may concern:

Be it known that I, ISADOR LEHMAN, a citizen of the United States of America, residing at Cleveland, in the county of Cuyahoga and State of Ohio, have invented certain new and useful Improvements in Engines Operated by Fluid Under Pressure; and I hereby declare the following to be a full, clear, and exact description of the invention, such as will enable others skilled in the art to which it pertains to make and use the same.

This invention relates to improvements in upright engines operated by fluid under pressure.

One object of this invention is the provision, in an upright engine, of such a simplified operative connection between the piston of the cylinder of the engine and the crank of the engine-shaft that the required reciprocations or movements of the piston and the connected pitman are not only materially shorter than would be the case if the said pitman were directly connected with the crank, but that the arrangement of the parts is convenient, that the number of parts required to form the aforesaid operative connection is reduced to a minimum, and that the provision of a guide-rod arranged parallel and movable with the piston-rod is accommodated.

Another object is to provide a simple and meritorious stationary framework for the engine, which framework is composed of members which are readily assembled and secured in place.

With these objects in view this invention consists in certain peculiarities of construction and arrangement and combinations of parts hereinafter described, and pointed out in the claims.

The accompanying drawing is a side elevation, largely in section, of the greater portion of an upright steam-engine embodying my invention.

Referring to the drawing, A designates the vertically-arranged cylinder of an upright steam-engine, a the piston contained within and adapted to operate endwise of the cylinder, and B the stationary framework of the engine.

The framework B comprises a horizontally-arranged base-plate 3, a horizontally-arranged top plate 5, and an intermediate horizontally-arranged plate 4. The plates 3, 4, and 5 are suitably spaced vertically and parallel. The intermediate plate 4 is ar-

ranged nearer the top plate 5 than to the base-plate 3. The base-plate 3 rests upon the floor or foundation C, upon which the engine is mounted. The framework B also comprises any suitable number of upright posts formed by rods 6, which extend vertically through correspondingly-arranged holes 2, formed in the plates 3, 4, and 5, and a suitable distance above and below the plates 5 and 3, respectively. The end portions of the rods 6 are screw-threaded externally, and correspondingly-screw-threaded nuts 7 are mounted on the said rods next below the base-plate 3, and the floor or foundation C is reduced, as at 8, to accommodate the location of the said nuts. Also nuts 10 are mounted on the rods 6 next above the base-plate 3. The nuts 7 and 10 secure the vertical posts formed by the rods 6 to the base-plate 3.

The plate 4 is mounted upon the upper ends of tubes 13, which embrace the rods 6 and extend between the said plate and the nuts 10 and rest upon the said nuts, and consequently upon the base-plate 3.

The top plate 5 rests upon the upper ends of tubes 14, which embrace and extend longitudinally of the rods 6 between the said plate 5 and the plate 4 and rest upon the last-mentioned plate. Nuts 12 are mounted on the rod 6 next above the top plate 5 and hold the said plate down upon the tubes 14. It will be observed, therefore, that the framework B is simple in construction and composed of sections which are readily assembled.

The cylinder A is mounted upon the plate 5. The rod or stem 15 of the piston a extends vertically through the lower head of the cylinder and through the top plate 5 into the space between the plates 4 and 5, and the plate 5 is slotted, as at 9, to accommodate the location and operation of the piston-rod.

The engine-shaft G is supported in any approved manner from the plate 3. The shaft G is arranged horizontally and at a right angle to the travel of the piston a, and g indicates the crank of the said shaft. The plate 3 is slotted, as at 16, to accommodate the location and operation of the shaft G and its crank g, and the floor or foundation C is recessed, as at 18, to accommodate the location and operation of the said crank. The shaft G is provided with a fly-wheel 17, and the floor or foundation C is recessed, as at 20, as shown in dotted lines, to accommodate the location of the said wheel.

An upright pitman *f* extends from the lower end of a piston-rod 15 downwardly and is pivoted at its upper end, as at 22, to the said rod horizontally and parallel with the engine-shaft. The plate 4 is slotted, as at 23, to accommodate the location and operation of the pitman *f*.

A lever *h* is arranged to oscillate in a vertical plane between the piston-rod 15 and the engine-shaft *G*. The lever *h* is journaled upon an axle *l*, which is arranged horizontally preferably exactly vertically above and parallel with the shaft *G*. The axle *l* is suitably supported from the plate 4, which is slotted, as at 24, to accommodate the location and operation of the lever *h*. The lever *h* is preferably an angular lever depending from the axle *l* and provided below the pitman *f* with an upwardly-projecting arm 25, to which the said pitman is pivoted at its lower end, as at 26, horizontally and parallel with the shaft *G*.

The pivotal connection between the lever *h* and the pitman *f* is arranged at one side of the axis of the said lever, and the lever *h* is operatively connected at the opposite side of its axis by means of a rod or link *m* with the crank *g* of the shaft *G*. The link *m* is pivoted at its upper end, as at 28, horizontally and parallel with the shaft *G* to the lever *h*. The link *m* at its lower end loosely embraces the wrist 27 of the crank *g*.

Between the axis of the lever *h* and the travel of the piston-rod 15 and parallel with the said travel is a vertically-arranged guide-rod *r*, which extends vertically loosely through the plates 4 and 5 and has lateral bearing in the said plates, and the piston-rod 15 and the guide-rod *r* are connected together between the said plates by a web 30, which is fixed in any approved manner to the said rods.

The peculiar shape of the lever *k* shown and hereinbefore described accommodates the location and operation of the guide-rod *r*.

The relative arrangement of the parts is such that the pivotal connection between the link *m* and the lever *h* is substantially as far from the axis of the said lever as from the pivotal connection between the lever *h* and the crank *g* and arranged lower than the pivotal connection between the pitman and the said lever, that the distance from the pivotal connection between the pitman *f* and the lever *h* to the axis of the said lever is approximately one-half the distance from the said axis to the pivotal connection between the lever and the link *m*, and that the pivotal connection between the lever and the pitman *f* is located farther than the axis of the lever from the pivotal connection between the lever and the link *m*.

What I claim is—

1. In an engine of the character indicated, a horizontally-arranged base-plate; a hori-

zontally-arranged top plate located a suitable distance vertically above the base-plate; an intermediate horizontally-arranged plate between and separate from the top plate and base-plate; vertically-arranged posts extending through the said plates and above and below the top plate and base-plate respectively and secured to the base-plate; tubes embracing the posts between the base-plate and the intermediate plate, which tubes rest upon the base-plate and bear the intermediate plate; tubes embracing the posts between the intermediate plate and the top plate and resting upon the intermediate plate and bearing the top plate; means for holding the top plate down upon the last-mentioned tubes; an engine-shaft supported from the base-plate; an upright engine-cylinder mounted on the top plate; the piston in the cylinder, which piston has its rod or stem depending through the lower head of the cylinder, and an upright pitman pivoted at its upper end horizontally and parallel with the shaft to the piston-rod and operatively connected at its lower end with the shaft, and the top plate being slotted to accommodate the location and operation of the piston-rod, the intermediate plate being slotted to accommodate the location and operation of the operative connection between the pitman and the shaft, and the base-plate being slotted to accommodate the location and operation of the crank.

2. In an engine of the character indicated, a horizontally-arranged base-plate; a horizontally-arranged top plate located a suitable distance vertically above the base-plate; an intermediate horizontally-arranged plate between and separate from the top plate and base-plate; vertically-arranged posts extending through the said plates and above and below the top plate and base-plate respectively and secured to the base-plate; tubes embracing the posts between the base-plate and the intermediate plate, which tubes rest upon the base-plate and bear the intermediate plate; tubes embracing the posts between the intermediate plate and the top plate and resting upon the intermediate plate and bearing the top plate; means for holding the top plate down upon the last-mentioned tubes; an engine-shaft supported from the base-plate and provided with a crank; an upright engine-cylinder mounted on the top plate; the piston in the cylinder, which piston has its rod or stem depending through the lower head of the cylinder; an upright pitman pivoted at its upper end horizontally and parallel with the shaft to the piston-rod; a lever supported from the intermediate plate and arranged with its axis parallel with the shaft, which lever is pivoted to the lower end of the pitman horizontally and parallel with and at one side of the axis of the lever, and a rod or link pivoted to the lever horizontally and

parallel with and at the opposite side of the axis of the lever and operatively connected with the crank of the shaft, and the top plate being slotted to accommodate the location 5 and operation of the piston-rod, the intermediate plate being slotted to accommodate the location and operation of the pitman and the lever, and the base-plate being slotted to accommodate the location and operation of the 10 crank.

3. In an engine of the character indicated, a horizontally-arranged base-plate; a horizontally-arranged top plate located a suitable distance vertically above the base-plate; an 15 intermediate horizontally-arranged plate between and separate from the top plate and base-plate; vertically-arranged posts extending through the said plates and above and below the top plate and base-plate respectively and secured to the base-plate; tubes 20 embracing the posts between the base-plate and the intermediate plate, which tubes rest upon the base-plate and bear the intermediate plate; tubes embracing the posts between the 25 intermediate plate and the top plate and resting upon the intermediate plate and bearing the top plate; means for holding the top plate down upon the last-mentioned tubes; an engine-shaft supported from the 30 base-plate and provided with a crank; an upright engine-cylinder mounted on the top plate; the piston in the cylinder, which piston has its rod or stem depending through the lower head of the cylinder; an upright pitman pivoted at its upper end horizontally and parallel with the shaft to the piston-rod; an axle located at one side of the travel of the pitman and supported from the intermediate 35 plate, which axle is arranged horizontally and parallel with the shaft; a lever journaled on and depending from the said axle, which lever is pivoted to the lower end of the pitman horizontally and parallel with and at one side of the axis of the lever, and a rod or link pivoted to the lever horizontally and parallel with and at the opposite side of the axis of the 40 lever and operatively connected with the crank of the shaft, and the top plate being slotted to accommodate the location and operation of the piston-rod, the intermediate 45 plate being slotted to accommodate the location and operation of the pitman and the lever, and the base-plate being slotted to accommodate the location and operation of the 50 crank.

4. In an engine of the character indicated, a horizontally-arranged base-plate; a horizontally-arranged top plate located a suitable distance vertically above the base-plate; an 55 intermediate horizontally-arranged plate between and separate from the top plate and base-plate; vertically-arranged posts formed

by rods having screw-threaded ends and extending through the said plates and above and below the top plate and base-plate respectively; nuts on the said rods at the upper side and lower side of the base-plate; tubes embracing the rods between the base-plate and the intermediate plate, which tubes rest upon the base-plate and bear the intermediate 65 plate; tubes embracing the rods between the intermediate plate and the top plate and resting upon the intermediate plate and bearing the top plate; nuts on the rods at the upper side of the top plate; an engine-shaft 70 supported from the base-plate and provided with a crank; an upright engine-cylinder mounted on the top plate; the piston in the cylinder, which piston has its rod or stem depending through the lower head of the cylinder, and an upright pitman pivoted at its upper end horizontally and parallel with the shaft to the piston-rod and operatively connected at the lower end with the shaft, and the top plate being slotted to accommodate 75 the location and operation of the piston-rod, the intermediate plate being slotted to accommodate the location and operation of the operative connection between the pitman and the shaft, and the base-plate being slotted to accommodate the location and operation of the crank.

5. In an engine of the character indicated, the stationary framework; the engine-shaft provided with a crank; an engine-cylinder 95 supported from the stationary framework a suitable distance from the shaft; the piston in the cylinder having its rod or stem extending toward the shaft; a pitman pivoted to the piston-rod and extending from the piston-rod 100 toward the shaft; a lever supported from the stationary framework and arranged between the pitman and the shaft with the axis of the lever parallel with the shaft, which lever has an arm projecting toward and pivoted to the 105 pitman horizontally and at one side of and parallel with the axis of the lever; a rod or link pivoted to the lever horizontally at the opposite side of and parallel with the axis of the lever and operatively connected with the 110 crank of the shaft, and a guide-rod arranged at one side of and parallel and operatively connected with the piston-rod, and the stationary framework affording bearing to the 115 said guide-rod.

In testimony whereof I sign the foregoing specification, in the presence of two witnesses, this 6th day of October, 1904, at Cleveland, Ohio.

ISADOR LEHMAN.
